UNITED STATES PATENT OFFICE.

WILLIAM C. STEWART, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

SPLITTING MACHINE.

Application filed February 20, 1919. Serial No. 278,198.

To all whom it may concern:

Be it known that I, WILLIAM C. STEWART, a subject of the King of England, residing at Swampscott, in the county of Essex and 5 State of Massachusetts, have invented certain Improvements in Splitting Machines, of which the following description, in connection with the accompanying drawings, is a specification, like reference characters on 10 the drawings indicating like parts in the several figures.

This invention relates to treating stock such as shoe stock and is herein described with particular reference to its use in even- 15 ing sole blanks.

In the manufacture of shoes it is customary to even sole blanks by running them through a splitting or skiving machine. Formerly it was the general practice to sort 20 the blanks for thickness putting in one group all the blanks from which say 12 iron soles could be produced, in another all those from which 11 iron soles could be produced, etc., after which the members of each 25 group of sole blanks were run through the splitting machine, the machine having been set properly once for each group. This practice still prevails to a large extent but has been superseded to some extent by an 30 other employing a machine to which the blanks are fed without previous sorting for thickness, such machine operating automatically to even each blank in accordance with its thickness.

According to the present invention a plurality of blank-engaging mechanisms are arranged in series, one mechanism being constructed to be responsive to blanks having a given degree of a selected characteristic and a succeeding mechanism being responsive to blanks having the selected characteristic in a different degree, the blanks being delivered from one mechanism to another until any given blank passes through 40 that mechanism which responds to it whereupon the blank is diverted from the machine before it reaches the next succeeding mech- 45 anism.

In the illustrative machine a plurality of 50 pairs of rolls are arranged in series, the first pair being adapted to be separated sufficiently by a blank of or above a given thickness to cause the blank after passing through the rolls to be diverted from the machine. The succeeding pairs of rolls are

adapted each to respond in the manner of the first pair to a thinner blank than is the preceding pair. The blanks, heterogeneous as to thickness, are fed one by one to the first pair of rolls and pass from pair to pair until any given blank reaches that pair which responds to its particular thickness, whereupon it is diverted from the machine. As thus far described, the machine may be used merely to sort blanks in accordance 65 with their thicknesses.

There may, if desired, be associated with each pair of rolls a knife for performing an evening operation on such blanks as the particular pair of rolls with which it is associated respond to, so that the blanks are evened as well as sorted; and in the illustrative machine such knives are embodied.

The illustrative machine comprises a series of evening mechanisms each including a 70 pair of rolls and a knife, the first mechanism being constructed to operate only upon blanks of or above a given thickness and the succeeding mechanisms being constructed to operate each upon a thinner blank than is the preceding mechanism; and transferring means, in the form of swinging chutes, 75 are provided which are capable of delivering a blank according to whether or not it has been evened, either to the succeeding 80 mechanism or to a locality outside the machine. In practice, receptacles are provided at the rear of each mechanism into which the chutes direct the blanks which have been 85 evened.

Referring now to the accompanying drawings,—

Fig. 1 is a central longitudinal section of a machine in which the present invention is embodied and by which the method of the 95 invention may be practised, one complete unit and part of a succeeding one being shown.

Fig. 2 is a side elevation of one of the 100 evening mechanisms, and

Fig. 3 is a plan of the machine shown in Fig. 1.

The evening, splitting or skiving mechanisms are all substantially alike except that each is constructed to operate upon a thinner blank than is the preceding one, and consequently only the leading one will be described in detail. Mounted in vertically 105 slidable bearings in the frame 5 are two opposed rolls, a feed roll 7 and a gage roll 9, 110

The gage roll is rotated from a driving pinion 11 through a large gear 13, which is fast to the shaft of the gage roll, and the shafts of the gage and the feed rolls are 5 geared together in the usual manner, not shown, to cause the rolls to rotate at equal velocities but in opposite directions. At the rear of the rolls is the usual splitting knife 15. The bearings of the feed roll 7 are held 10 up against the usual stops by the usual heavy springs and the upward movement of the gage roll 9 is limited by contact of inclines on the tops of the bearings with the usual wedges 17, which may be adjusted 15 lengthwise of the roll. The construction, which has been briefly outlined above and is only partially shown in the drawings, is old and well known, and an example of it may be seen in detail in the patent to Nash 20 No. 894,850.

Ordinarily the gage roll is normally held to the upper limit of its bodily movement, but in the present machine this roll 9 is held normally down in contact with the feed roll 25 by springs 19 which bear at their lower ends against lugs formed on the bearings of the roll shaft and at their upper ends against the frame of the machine, these springs being of less strength than those which support the lower roll. When a sole blank is presented to the rolls, the first effect of its entry between the rolls is thus to lift the gage roll, and this movement is utilized to control the locking and unlocking of a transmitting or delivery means in the form of a chute 21. This chute is fast to or integral 30 with a sleeve 23 which is rotatably mounted on a rotary shaft 25 and is normally held in the horizontal position shown, so as to deliver to the succeeding mechanism a blank which has passed through a preceding mechanism, by a spring 27 (Fig. 3) coiled about the shaft 25 and having one end fast to the sleeve 23 and the other fast to a stationary 40 headed sleeve 29 which is loose on the shaft but fastened by a set screw 30 to the frame of the machine and may be adjusted about the shaft, if desired, to vary the tension of the spring.

45 In order to lock the chute in the position shown and to unlock it again, all for a purpose which will presently appear, a catch 31, pivoted at 33 to the frame of the machine, has a tail provided with a projection 35, the weight of the tail being sufficient when unopposed, to rock the catch about its pivot into position to engage an arm 37 which is fast to or integral with the sleeve 23 and hence with the chute 21. A lever 39, 50 pivoted at 41 to the frame of the machine and at 43 to one of the bearings of the gage roll shaft, normally engages the underside of the projection 35 with its free end and is adapted to have the free end moved up over 55 the projection if the gage roll is moved suffi-

ciently upwards. The catch 31 is thus moved for a short interval out of engagement with the locking arm 37 every time a blank is fed between the rolls of the machine. If the blank is not thick enough 70 to raise the upper roll to its limit and in addition to depress the lower roll more or less, then the chute remains in its horizontal position, and the blank passes over the knife 15 through the chute and is delivered to the 75 succeeding mechanism.

The blank is fed along the chute by driven rollers 45 and co-operating idle rollers 47, the driven rollers being rotated by a chain 49 which passes around sprockets 51 on the 80 roller shafts and around a sprocket on the shaft 25. The shaft 25 is driven by a gear 53 fast to the shaft which meshes with a pinion 55, said pinion being fast to a short shaft which also carries a gear 57, the last-named gear meshing with a large gear 59 fast to the shaft of the lower roll. The idle presser rollers 47 are rotatably mounted on the forward ends of arms 61 the rear ends of which, except those of the rearmost one, 90 are pivoted at 63 to rods carried by the walls of the chute. The arms 61 of the rearmost presser roller 47 are pivoted about alined studs carried by the frame of the machine, the hubs of the arms encircling these studs and being held in place by screws 64. Springs 65 hold the presser rolls yieldingly down upon the blank, and members 67 integral with the arms 61 hold the blanks down and direct their forward ends to the 100 feed of the feed and idle rollers of the chute.

In order to swing the chute downwardly about the axis of the shaft 25 when a blank of sufficient thickness to be operated upon is presented to the evening mechanism, a downwardly extending arm 69, which is integral with the rear end of the chute, carries a long bar 71 which extends through the machine from side to side. A pair of springs 73, which are normally under no tension but are stronger than the coiled spring 27 which maintains the chute normally in its horizontal position, are connected to the bar 71 so that a pull exerted upon the bar 71 through these springs will swing the chute downwardly to cause a blank to be delivered from the series of mechanisms preferably into a receptacle 75. These springs 73 are connected at their rear ends respectively to rocker arms 77, each rocker arm being pivoted at 79 to a plunger 81 which is vertically slidable in a socket member 83 and is normally held in the position shown by a spring 85, said position being adjustable by means of an adjusting nut 87 threaded upon the reduced end of the plunger. A lock nut 89 ensures the permanence of this adjustment. Each rocker arm has at its upper end a segmental portion triangular in cross-section which is always in register, but normally not 115 120 125 130

in contact, with a grooved collar 91 carried by the shaft of the lower or feed roll 7. When the feed roll is depressed sufficiently to cause the knife to remove a skiving from a blank—that is when a sufficiently thick blank is presented to the machine—the collars 91 engage the rocker arms 77 frictionally and swing them to the left, as viewed in Figs. 1 and 2, thereby swinging the chute 5 downwardly into position to deliver the skived or evened blank to the receptacle 75. In order to hold the chute in its downward position after the rear end of the blank has passed from between the rolls of the evening 10 mechanism, a latch 93 is arranged to engage at the proper time a small roller 95 mounted on the lower end of the arm 69. This latch is pivoted at 97 to the frame of the mechanism and has an upwardly extending tail 15 which is guided in a groove in the feed roll and extends into the path of the blanks which are presented to the mechanism, so that the first effect of presenting a blank to the mechanism is to swing the latch in a 20 clockwise direction about its pivot 97. A spring 99, fastened to the latch and to the frame of the machine, tends at all times to pull the operative end of the latch up into the path of the roller 95 on the arm 69, but, 25 until the rear end of the blank rides off the tail of the latch, this spring is ineffective.

The operation of the machine will now be described. In the drawings there has been shown only one evening mechanism 30 and chute complete and part of a following evening mechanism. It may be that in some instances two units arranged in series would be satisfactory, but usually three or more will be required. The first mechanism is 35 constructed—in the present instance adjusted—to operate only upon blanks above a given thickness, and the remaining mechanisms are constructed each to operate upon a thinner blank than is the preceding mechanism. The sole blanks come to the operator of the present machine in a collection which is heterogeneous, among other characteristics, as to thickness; and the operator merely presents them one by one to the first 40 mechanism of the series. Assuming that a blank, which is presented to the machine, is too thin to be operated upon by the first mechanism but sufficiently thick to be operated upon by the second mechanism, the effect of the blank upon the mechanisms and the final result to the blank will be as follows.

Referring more particularly to Figs. 1 and 2, as the blank is presented to the rolls 45 its forward end first rides over the tail of the latch 93, thereby swinging the operative end of the latch downwardly. Next it lifts the gage roll 9 and thereby shifts the free end of the lever 39 over the projection 35 on 50 the catch 34. Inasmuch, however, as the

blank is not thick enough to depress the feed roll 7, there is no swinging of the chute, and the blank passes over the knife and is transferred by the rolls 45 and 47 of the chute to the next mechanism. As soon as 70 the rear end of the blank has passed from between the rolls 7, 9 of the first mechanism, the gage roll 9 is pushed down by the springs 19, and the lever 39 returns to the position shown. Previously the spring 99 75 has returned the latch 93 to the position shown so that the mechanism is all set to receive another blank.

Turning now to the first blank which has just been presented to the second mechanism, 80 it will be understood that the second mechanism is exactly like the first except that the gage roll is permitted to move upwardly a shorter distance. It may accordingly be assumed, for purposes of explanation, that 85 the figures of the drawing show this second mechanism. As the forward end of the blank enters the mechanism, the tail of the latch 93 is depressed and the gage roll moved upwardly to the extent of its movement, 90 thereby disengaging for an interval the catch 31 from the locking arm 37. During or just prior to this interval the lower roll 7 is depressed thereby causing the collars 91 to engage the rocker arms 77; and, during 95 the interval in which the catch 31 remains disengaged, the arms 77 are rocked to the left to swing the chute down into position to deliver the blank to the receptacle. This swinging of the chute results from the 100 swinging of the arm 69 so that presently the roller 95 on the end of the arm moves to the left past the hook on the end of the latch 93. The spring 99 is at this time under tension to pull the latch 93 up into the 105 path of return of the roller 95, but is prevented from doing so by the engagement of the blank with the tail of the latch. As soon, however, as the rear end of the blank rides off the tail of the latch, said latch 110 rises under the force of the spring 99 so that when the rear end of the blank passes from between the bite of the rolls 7 and 9 and there is no further pull by the rocker arms 77 to hold the chute down in position 115 to deliver the blank to the receptacle, the holding of the chute is accomplished by the engagement of the latch with the roller 95. At the same time that the rear end of the blank passes from between the bite of the 120 rolls 7 and 9, the gage roll 9 moves down to its initial position thereby moving the end of the lever 39 from a position above the projection 35 to one below it. The blank, which has been operated upon, is 125 then delivered by the chute to the receptacle. The first result of presenting another blank to the mechanism is to release the latch 93 from the roller 95, whereupon the coiled spring 27 returns the chute to its nor-

mal horizontal position, and the parts of the mechanism are in the positions shown in the drawings. In the course of the return of the chute to normal position the arm 37 strikes the catch 31 a sharp blow. In order to prevent any considerable movement of the catch about its pivot, as a result of this blow, the catch is provided on its rear, as viewed in the figures, with a rib 32 over 10, which a curved finger 34 on the arm 37 passes, there being, of course, enough space between the rib and finger to permit the catch to be swung at any time by the arm 39 about the pivot 33 sufficiently to unlock 15 the arm 37. The passing of a blank through only two units of the machine has been described, but obviously its passage through succeeding units would involve nothing which has not been explained. And al- 20 though only one complete unit and part of another have been shown in the illustrative series, it should be understood that as many units as may be desired may be used.

The operation of the mechanism has been described thus far on the assumption that each blank presented to the rolls 7 and 9 is of substantially uniform thickness throughout. This condition, however, does not always obtain and a part of the blanks will be 25 considerably thinner at one end than at the other or will have a thin locality somewhere between the ends or will differ otherwise in thickness at different localities. In order to promote brevity, let it be supposed that a given blank is thick enough at the ends 30 to be evened by the first mechanism but has a locality between the ends extending across the blank which is too thin to be operated upon by the mechanism. If it were not for 35 the catch 31 and its associated parts such a blank would be delivered into the receptacle as a finished blank; but it would be unsuitable for use in a shoe because of the thin spot and should have been carried on to 40 succeeding mechanisms until it had been properly evened throughout. If such a blank is presented to the machine, the operation is as follows: The forward portion of the blank lowers the latch 93, moves the gage 45 roll upwardly to disengage the catch 31, and moves the presser roll downwardly, thereby 50 pulling the chute down. The splitting operation goes on with the parts in the positions which have been indicated until the 55 rolls encounter the thin locality. When this occurs, the feed roll rises so that there is no longer any pull exerted through the rocker arms 77 to hold the chute in its inclined position. At once the coiled spring 27 returns 60 the chute to its horizontal position, the end of the locking arm 37 being engaged with the catch 31. The blank then passes along without being operated upon until the thick 65 portion at the rear of the blank is encoun- tered. When this occurs, the presser roll 7

is again depressed and the rocker arms 77 are swung to the left. Inasmuch, however, as the free end of the lever 39 is still above the projection 35, the catch 31 is not disengaged from the locking arm 37, and the chute can- 70 not be swung downwardly. Instead, it re- mains in its horizontal position, the springs 73 yielding to prevent breakage of parts. Consequently such a blank will be delivered from mechanism to mechanism until it reaches a mechanism capable of operating 75 upon its thin locality. Similarly a blank having one end too thin to be operated upon, whether it is presented with the thin end or with the thick end first will pass on to the 80 succeeding mechanism. In cases such as those indicated above the blank will thus be evened approximately to the thickness of its thinnest portion. It should be under- 85 stood, however, that the mechanism of each unit, if not provided at all with the catch 31 and its associated parts, will operate to de- 90 liver a run of blanks, the members of which are of substantially uniform although not the same thickness throughout, either to the receptacles or to the succeeding mechanism according to whether they have or have not been operated upon.

Having thus described my invention, what I claim as new and desire to secure by Let- 95 ters Patent is:

1. A machine of the class described hav- 100 ing, in combination, a plurality of mech- anisms arranged in series, one mechanism being constructed to perform an operation upon blanks of a given degree of a selected characteristic and each succeeding mech- 105 anism being constructed to perform an operation upon blanks possessing the selected characteristic in a different degree, means for delivering blanks from one mechanism to another, and means operating automatic- 110 ally to divert each blank from the series as soon as it has been operated upon by any one of the mechanisms but to permit 115 the blank to pass from mechanism to mech- anism until it has been operated upon.

2. A machine of the class described, hav- 120 ing in combination, a plurality of mech- anisms arranged in series, one mechanism being constructed to perform an operation upon blanks of a given degree of a selected characteristic and a succeeding mechanism being constructed to perform an operation upon blanks possessing the selected char- 125 acteristic in a different degree, means for de- livering a blank from one mechanism to another, and means responsive to the degree of the selected characteristic possessed by a given blank for diverting said blank.

3. A machine of the class described, hav- 130 ing in combination, a plurality of mech- anisms arranged in series, one mechanism being constructed to operate upon blanks of or above but not below a given degree of a

selected characteristic and a succeeding mechanism being constructed to operate upon blanks possessing the selected characteristic in a lesser degree than is the preceding mechanism, means for delivering blanks from one mechanism to another until it has been operated upon, and means responsive to the movements of a preceding mechanism during its operation upon the blank for diverting the blank before it reaches the succeeding mechanism.

4. A machine of the class described, having in combination, a plurality of mechanisms arranged in series, one mechanism being constructed to operate upon blanks of or above but not below a given degree of a selected characteristic and a succeeding mechanism being constructed to operate upon blanks possessing the selected characteristic in a lesser degree than is the preceding mechanism, means for delivering blanks from one mechanism to another, and means responsive to the degree of the selected characteristic possessed by a given blank for diverting said blank.

5. A machine of the class described, having in combination, a plurality of mechanisms arranged in series, one mechanism being constructed to operate upon blanks of or above but not below a given degree of a selected characteristic and a succeeding mechanism being constructed to operate upon blanks possessing the selected characteristic in a lesser degree than is the preceding mechanism, means for delivering blanks from one mechanism to another, and means responsive to the degree of the selected characteristic possessed by a given blank for controlling the operation of the delivering means.

6. A machine of the class described, having in combination, a plurality of mechanisms arranged in series, one mechanism being constructed to perform an operation upon blanks of or above but not below a given degree of a selected characteristic and a succeeding mechanism being constructed to perform an operation upon blanks possessing the selected characteristic in a lesser degree than the preceding mechanism, and transferring means responsive to the degree of the characteristic possessed by any given blank capable of delivering that blank from one mechanism either to a succeeding mechanism or to a locality outside the machine.

7. A machine of the class described, having in combination, a plurality of mechanisms arranged in series, one mechanism being constructed to perform an operation upon blanks of or above but not below a given degree of a selected characteristic and a succeeding mechanism being constructed to perform an operation upon blanks possessing the selected characteristic in a

lesser degree than the preceding mechanism, and transferring means capable of delivering a blank from one mechanism either to a succeeding mechanism or to a locality outside the machine, said means being responsive to the degree of the selected characteristic possessed by the blank.

8. A machine of the class described, having in combination, a plurality of mechanisms arranged in series one mechanism being constructed to perform an operation upon blanks of or above but not below a given degree of a selected characteristic and a succeeding mechanism being constructed to perform an operation upon blanks possessing the selected characteristic in a lesser degree than the preceding mechanism, transferring means capable of delivering a blank from one mechanism either to a succeeding mechanism or to a locality outside the machine, and means responsive to the degrees of the selected characteristic possessed by the blanks for controlling their delivery.

9. A machine of the class described, having, in combination, a plurality of dimension-reducing mechanisms arranged in series, one mechanism being constructed to operate upon blanks of or above but not below a given extent of a selected dimension and a succeeding mechanism being constructed to operate upon a blank of less extent in said dimension, means for transferring a blank from one mechanism to another, and means responsive to the dimension of the blank for diverting the blank from the series.

10. A machine of the class described, having in combination, a plurality of dimension-reducing mechanisms arranged in series, one mechanism being constructed to operate upon blanks of or above but not below a given extent of a selected dimension and a succeeding mechanism being constructed to operate upon a blank of less extent in said dimension, means for transferring a blank from one mechanism to another, and means responsive to the extent of the selected dimension for diverting the blank from the series.

11. A machine of the class described, having in combination, a plurality of splitting mechanisms arranged in series, one mechanism being constructed to operate upon blanks of or above but not below a given thickness and a succeeding mechanism being constructed to operate upon thinner blanks and transferring means responsive to the thickness of a blank capable of delivering a blank from one mechanism either to a succeeding mechanism or to a locality outside the machine.

12. A machine of the class described, having in combination, a plurality of splitting mechanisms arranged in series, one mechanism being constructed to operate upon blanks of or above but not below a given

thickness and a succeeding mechanism being constructed to operate upon thinner blanks and transferring means capable of delivering a blank from one mechanism, either to a succeeding mechanism or to a locality outside the machine, said means being responsive in its operation to the thickness of the blank.

13. A machine of the class described, having in combination, a plurality of splitting mechanisms arranged in series, one mechanism being constructed to operate upon blanks of or above but not below a given thickness and a succeeding mechanism being constructed to operate upon thinner blanks, transferring means capable of delivering a blank from one mechanism either to a succeeding mechanism or to a locality outside the machine, and means responsive to the thickness of the blanks for controlling their delivery.

14. A machine of the class described, having in combination, a plurality of splitting mechanisms arranged in series, one mechanism being constructed to operate upon blanks of or above but not below a given thickness and a succeeding mechanism being constructed to operate upon thinner blanks, delivering means located between the mechanisms, and means responsive to the thickness of the blank for causing the delivering means to deliver a blank from mechanism to mechanism along the series until the blank has been operated upon and then to divert the blank from the series.

15. A machine of the class described, having in combination, a plurality of splitting mechanisms arranged in series, one mechanism being constructed to operate upon blanks of or above but not below a given thickness and a succeeding mechanism being constructed to operate upon thinner blanks, a chute movable into one position to direct blanks from one mechanism to the other and into another position to direct blanks outside the series, and means responsive to the thicknesses of the respective blanks for operating the chute.

16. A machine of the class described, having in combination, a plurality of splitting mechanisms arranged in series, one mechanism being constructed to operate upon blanks of or above but not below a given thickness and a succeeding mechanism being constructed to operate upon thinner blanks, a chute normally held in position to direct blanks from one mechanism to the other, and means responsive to the operation upon a blank by one mechanism for moving the chute into position to deliver that blank outside the series.

17. A machine of the class described, having in combination, a plurality of splitting mechanisms arranged in series, one mechanism being constructed to operate upon

blanks of or above but not below a given thickness and a succeeding mechanism being constructed to operate upon thinner blanks, a chute normally held in position to direct blanks from one mechanism to the other but movable to another position, and means responsive to the thickness of each blank passed through the leading mechanism for controlling the position of the chute.

18. A machine of the class described, having in combination, a plurality of splitting mechanisms arranged in series, one mechanism being constructed to operate upon blanks of or above but not below a given thickness and a succeeding mechanism being constructed to operate upon thinner blanks, a chute normally locked in position to deliver blanks from one mechanism to the other, and means for unlocking the chute and for moving it into a position to divert blanks from the machine.

19. A machine of the class described, having in combination, a plurality of splitting mechanisms arranged in series, one mechanism being constructed to operate upon blanks of or above but not below a given thickness and a succeeding mechanism being constructed to operate upon thinner blanks, a chute normally locked in position to deliver blanks from one mechanism to the other, and means operated by a blank as it passes through a mechanism and responsive to the thickness of the blank for unlocking the chute and moving it into a position to divert the blank from the machine.

20. A machine of the class described, having in combination, a plurality of splitting mechanisms each comprising separable feed rolls and a knife, arranged in series and constructed each to operate upon a thinner blank than is the preceding mechanism, means capable of delivering blanks from each mechanism except the last one, either to the succeeding mechanism or to a locality outside the machine, and means responsive to the extent of separation of the rolls for controlling the operation of the delivery means.

21. A machine of the class described, having in combination, a plurality of splitting mechanisms, each comprising separable feed rolls and a knife, arranged in series and constructed each to operate upon a thinner blank than is the preceding mechanism, a chute located between each two mechanisms normally in position to deliver a blank from one mechanism to the other, a lock for holding the chute in this position, means operated by bodily movement of one of the rolls for unlocking the chute, and means operated by bodily movement of the other roll for moving the chute into position to shunt a blank from the series.

22. A machine of the class described, hav-

ing in combination, a plurality of splitting mechanisms arranged in series and constructed each to operate upon a thinner blank than is the preceding mechanism, each mechanism except the last comprising a feed roll, a gage roll bodily movable toward and from each other, means for causing a blank presented to the mechanism to move the gage roll before it moves the feed roll, a chute extending from the rear of the mechanism, means controlled by the gage roll for locking and unlocking the chute, and means controlled by the feed roll for moving the chute.

23. A splitting mechanism, a chute located in the rear thereof and movable into two positions to deliver blanks to either of two localities, means for locking the chute in position to deliver to one locality, means operated by a blank in its passage through the mechanism for unlocking the chute, moving it into position to deliver to the other locality and for locking it in the last-named position, and means responsive to the presentation of a succeeding blank to the mechanism for unlocking the chute, returning it to its first-named position and locking it again.

24. A machine of the class described, having, in combination, a plurality of splitting mechanisms arranged in series, one mechanism being constructed to operate upon blanks of or above but not below a given thickness and a succeeding mechanism being constructed to operate upon thinner blanks, transferring means movable into two positions either to deliver a blank from one mechanism to the succeeding mechanism or to divert it to a point outside the machine, means responsive to a locality in a blank thick enough to be operated upon for moving the transferring means to diverting position, and means responsive to a succeeding locality not thick enough to be operated upon for moving the transferring means to delivering position.

25. A machine for operating upon a blank of uneven thickness, having in combination, a plurality of splitting mechanisms arranged in series, one mechanism being constructed to operate to some extent upon a blank having a locality of or above a given thickness and a succeeding mechanism being constructed to operate upon a blank having a locality of less than the given thickness, transferring means capable of being operated to deliver the blank from the first mechanism either to the succeeding mechanism or to a point outside the machine, and means responsive to the thickness of the thinnest locality of the blank for controlling the operation of the transferring means.

26. A machine for operating upon blanks of different thicknesses, having in combina-

tion, a plurality of splitting mechanisms arranged in series, each succeeding mechanism being adapted to operate upon thinner blanks than is the preceding mechanism, and means responsive to the thickness of a blank presented to the machine for transferring it from mechanism to mechanism until it has been operated upon.

27. A machine for operating upon blanks of different thicknesses, having in combination, a plurality of splitting mechanisms arranged in series, each succeeding mechanism being adapted to operate upon thinner blanks than is the preceding mechanism, means responsive to the thickness of a blank presented to the machine for transferring it from mechanism to mechanism until it has been operated upon, and means for thereafter diverting it from the series.

28. A machine of the class described, having in combination, a plurality of sets of selective blank-engaging mechanisms arranged in series each succeeding mechanism being constructed and arranged to be responsive to a thinner blank than is the preceding mechanism, means for delivering the blanks from one mechanism to another, and means responsive to the thickness of any given blank for diverting blanks from the series.

29. A machine of the class described, having in combination, a plurality of sets of selective blank-engaging mechanisms arranged in series each succeeding mechanism being constructed and arranged to be responsive to a thinner blank than is the preceding mechanism, means for delivering the blanks from one mechanism to another, and automatic means responsive to the thicknesses of the blanks for diverting each blank from the series after it has been engaged by that mechanism which responds to its particular thickness and before it reaches the next succeeding mechanism.

30. A machine of the class described, having in combination, a series of pairs of rolls, the rolls of each pair being separated from each other by a distance less than that by which the preceding pair is separated, means for delivering a blank from one pair to another of the series until the blank is engaged by that pair the distance between which is set to respond to the thickness of the blank, and means operating then to divert the blank from the series.

31. A machine of the class described, having in combination, a plurality of sets of selective blank-engaging mechanisms arranged in series, each succeeding mechanism being constructed and arranged to be responsive to a thinner blank than is the preceding mechanism, means for moving a blank in a path to present it from one mechanism to another, and means operated by that mechanism which is arranged to be responsive

- to the thickness of that particular blank for diverting the blank from the path and thereby preventing its reaching the next succeeding mechanism.
- 5 32. A machine for sorting blanks in accordance with their thicknesses, having in combination, a plurality of pairs of members, one member of each pair being arranged to be moved away from the other by the 10 passage of a blank between them, means for delivering a blank from one pair to the succeeding pair, and means controlled by the amount of separation of the members for diverting the blank from the machine.
- 15 33. A machine for sorting blanks in accordance with their respective thicknesses, having in combination, a plurality of sets of rolls, one member of each set being arranged to be moved away from the other by the 20 passage of a blank between them, means for delivering a blank from one set to the succeeding set, and means controlled by the amount of separation of the rolls for diverting the blank from the machine.
34. A machine of the class described, having in combination, a plurality of blank-engaging mechanisms arranged in series, one mechanism being constructed to be responsive to blanks having a given degree of a selected characteristic, and a succeeding 25 mechanism being responsive to blanks having the selected characteristic in a different degree, means for delivering blanks from one mechanism to another, and means for diverting each blank from the machine as soon as it has passed through that mechanism which responds to its particular degree of the selected characteristic.

In testimony whereof I have signed my name to this specification.

WILLIAM C. STEWART.
